US00D986915S

(12) **United States Design Patent** (10) Patent No.: **US D986,915 S**
 (45) Date of Patent: **** May 23, 2023**

(54) **DISPLAY SCREEN WITH GRAPHICAL USER INTERFACE FOR PRESENTING WEBSITE ANALYTICS**

(71) Applicant: **Siteimprove A/S**, Copenhagen (DK)

(72) Inventor: **Christoffer Lund Stroier**, Copenhagen (DK)

(73) Assignee: **SITEIMPROVE A/S**, Copenhagen (DK)

(**) Term: **15 Years**

(21) Appl. No.: **29/851,248**

(22) Filed: **Aug. 26, 2022**

Related U.S. Application Data

(63) Continuation of application No. 29/771,363, filed on Feb. 22, 2021, which is a continuation of application No. 29/621,701, filed on Oct. 10, 2017, now Pat. No. Des. 911,352.

(51) **LOC (14) Cl.** **14-04**

(52) **U.S. Cl.**

USPC **D14/485**

CLAIM

The ornamental design for a display screen with graphical user interface for presenting website analytics, as shown and described.

DESCRIPTION

The FIGURE is a front view of a display screen with a graphical user interface for presenting website analytics. The broken lines showing a display screen and elements of the graphical user interface, including the thick circular broken lines illustrate portions of the article, and form no part of the claimed design.
